UNITED STATES PATENT OFFICE.

ETHEL H. KLAMROTH, OF PASADENA, CALIFORNIA.

DESIGN FOR A SMOCKED GARMENT.

49,093.

Specification for Design.

Patented May 23, 1916.

Application filed March 30, 1916. Serial No. 87,859. Term of patent 3½ years.

To all whom it may concern:

Be it known that I, ETHEL H. KLAMROTH, a citizen of the United States, residing at Pasadena, in the county of Los Angeles and State of California, have invented a new, original, and ornamental Design for Smocked Garments, of which the following is a specification, reference being had to the accompanying drawing, forming part thereof.

The figure is a front elevation view of a smocked garment, showing my new design.

I claim:

The ornamental design for a smocked garment, as shown.

ETHEL H. KLAMROTH.
